UNITED STATES PATENT OFFICE.

WALTER F. SCHNEIDER, OF OAKLAND, CALIFORNIA.

DESIGN FOR A TORCHÈRE.

Application filed February 24, 1928. Serial No. 25,555. Term of patent 14 years.

To all whom it may concern:

Be it known that I, WALTER F. SCHNEIDER, a citizen of the United States, residing at Oakland, in the county of Alameda, State of California, have invented a new, original, and ornamental Design for a Torchère, of which the following is a specification, reference being had to the accompanying drawing, forming part thereof.

The figure is a front view of a torchère showing my new design.

I claim:

The ornamental design for a torchère as shown.

WALTER F. SCHNEIDER.
